CLAIM

The ornamental design for a sample consumable, as shown and described.

DESCRIPTION

FIG. 1 is the front elevation view of a sample consumable showing my new design;

FIG. 2 is a side elevation view thereof;

FIG. 3 is an isometric view thereof;

FIG. 4 is a rear elevation view thereof;

FIG. 5 is a section view thereof; and,

FIG. 6 is a top plan view thereof.

The broken line showing of sample consumable is included for the purpose of illustrating portions of the “article” and forms no part of the claimed design.
